Primary Examiner — Darlington Ly

(57) **CLAIM**

The ornamental design for a patient transfer device, as shown and described.

DESCRIPTION

1.1 is a top, front and right-side perspective view of a patient transfer device embodying our new design;

1.2 is a top, front and right-side perspective view thereof in an extended position;

1.3 is a bottom, rear and left-side perspective view thereof;

1.4 is a front elevation view thereof;

1.5 is a rear elevation view thereof;

1.6 is a top plan view thereof;

1.7 is a left-side elevation view thereof;

1.8 is a right-side elevation view thereof; and

1.9 is a bottom plan view thereof.

1 Claim, 9 Drawing Sheets
